REINFORCING SEAM FOR OVERNIGHT,
BATHING, AND OTHER BAGSHarry Dubofsky, Brooklyn, and Joseph Alhadef,
Rockaway Beach, N. Y.

Application January 29, 1940, Serial No. 316,124

5 Claims. (Cl. 190—54)

This invention relates to new and useful improvements in a reinforced seam for overnight, bathing and other bags.

More specifically, the invention proposes the construction of a bag characterized by a flexible sheet of relatively soft material forming one wall thereof and a second sheet of flexible soft material forming a second wall of said sheet, and a novel type of seam for connecting together the adjacent edges of these sheets.

Still further it is proposed to characterize the seam by turning the edges of the sheets inwards and mounting a welt between these inturned edges and to secure the edges together by means of a line of stitches in such a manner that the welt will be disposed therebetween.

Still further it is proposed to provide a flexible tubular casing mounted on one of the edges and through which a stiff flexible wire has been extended in a manner to add rigidity to the bag and to provide a pair of bound stiff flexible strips for connecting and reinforcing the said flexible wires and the bag.

Still further the invention proposes that the flexible tubular casing enclosing the flexible wire have side edge flanges adapted to be folded to engage into the junction of the sheet to which it is attached and its inturned edge in a manner to more definitely define the outline of the bag.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of an overnight, bathing or the like bag constructed in accordance with this invention.

Fig. 2 is a sectional view of the bag taken between the side walls thereof.

Fig. 3 is an enlarged sectional view on the line 3—3 of Fig. 1.

Fig. 4 is a sectional view of the top wall of the bag.

Fig. 5 is a sectional view of the side wall of the bag.

Fig. 6 is an enlarged sectional view on the line 6—6 of Fig. 1.

Fig. 7 is a view similar to Fig. 3 but illustrating a modification of the invention.

Fig. 8 is a view similar to Fig. 7 illustrating an adjusted position of the tubular casing.

Fig. 9 is a sectional view taken on the line 9—9 of Fig. 7.

Fig. 10 is a sectional view taken on the line 10—10 of Fig. 2.

Fig. 11 is a sectional view taken on the line 11—11 of Fig. 10.

The reinforced seam for overnight, bathing and other bags, according to this invention, is to be applied to a bag having a flexible sheet of relatively soft material 10 forming a wall of the bag and having an inturned edge 10^a. This sheet of material 10 preferably forms the top, end and bottom walls of the bag. A second sheet of flexible relatively soft material 11 is arranged at an angle relative to the sheet 10 and has an inturned edge 11^a. This sheet of relatively soft material 11 forms the side wall of the bag. The inturned edges 10^a and 11^a preferably extend parallel to each other.

A welt 12 is disposed between the inturned edges and is mounted on one of these edges. This welt 12 preferably comprises a tubular casing 12^a having edges extending between the edges 10^a and 11^a. The welt 12 further includes a piece of cord or string 12^b extended through the tubular casing 12^a. This tubular casing 12^a is securely attached, preferably to the inturned edge 11^a by means of a line of stitches 13 as shown in Fig. 5.

A flexible tubular casing 14 is secured to the other of the edges. This tubular casing 14 is preferably constructed of soft material and has projecting edges 14^a which are preferably attached to the inturned edge 10^a by means of a line of stitches 15 as shown in Fig. 4. A stiff flexible wire 16 extends through the tubular casing 14 and is provided for adding rigidity to the bag to cause the bag to maintain its shape under the weight of articles placed therein.

Connecting strips 12' are provided for reinforcing each end 10' of the bag, and to keep welts 12 in fully spaced condition. Each strip 12' consists of a stiff flexible strip 16' and is surrounded by a tubular leather or like casing 16^a. A leather or like binding 16^b is stitched over the open edge of the tubular casing.

The connecting strips 12' are adjacent to but are free from the end 10' of the bag, and are connected to the edges 11^a by a line of stitches 17 (see Figs. 3 and 10) which is provided for securing the edges 10^a and 11^a together with the welt 12 disposed therebetween. These stiches 17 pass through the edges 10^a, 11^a and the casing 12^a of the welt 12. As noted in Fig. 3, the stiches 17 pass through the casing 12^a of the welt 12 between the stiches 13 and the cord or thread 12^b.

The sheet of material 10 across the top portion is provided with an opening 10^b closed by means of a conventional slide fastener 18. The bag is further provided with a pair of handles attached to the sheets of material 11, forming the side walls, for permitting the bag to be conveniently carried.

These handles are also formed in a novel manner and comprise a strip of soft flexible material 20 having the edges 20^a doubled upon itself and secured to the intermediate portion thereof

by lines of stitches 21. This construction forms a pair of passages 20^b at the sides of the flexible material 20 through which stiff flexible wires 22 are extended for imparting rigidity to these handles to cause them to maintain their looped shape, as shown in Fig. 2, under the weight of articles placed within the bag.

A strip of leather 23 extends over the contacting edges 20^a of the sheet of flexible material 20 and is secured thereto by means of stitches 23' for concealing these edges from view and for adding to the decorative effect thereof. The ends of the flexible material 20 are secured in position between the sheets of material forming the side walls and member 24 which are extended thereover as shown in Fig. 1.

According to the modification of the invention shown in Figs. 7 to 9 inclusive, the construction of the seam is similar to that previously described except that the tubular casing 14' has wide projecting edge flanges 14^b which are secured to the inturned edge 10^a by means of a line of stitches 15'. These projecting edge flanges 14^b are formed with second line of stitches 15'', immediately adjacent the stiff wire 16 for holding the wire in position adjacent the free edge of the flanges. These flanges may project into the bag as shown in Fig. 7 or the flanges may be bent to the position illustrated in Fig. 8 to cause the wire 16 to engage the junction of the sheet of material 10 and its inturned edge 10^a for the purpose of more definitely defining the outline of the bag.

A means is provided for holding the flanges 14^b in this turned over position and comprises snap fastener elements 25 attached to the face of the flange 14^b and which are adapted to be engaged with complementary snap fastener elements 26 mounted upon the adjacent face of the inturned edges 10^a. In other respects this form of the invention is similar to the previous form 40 and like parts are identified by like reference numerals.

While we have illustrated and described the preferred embodiments of our invention, it is to be understood that we do not limit ourselves to the precise constructions herein disclosed and the right is reserved to all changes and modifications coming within the scope of the claims.

Having thus described our invention, which we claim as new, and desire to secure by United States Patent is:

1. A reinforced seam for bags, comprising a flexible sheet of relatively soft material forming a wall for the bag and having an inturned edge, another flexible sheet of relatively soft material at an angle to said sheet and forming another wall of said bag and having an inturned edge, a welt disposed between said inturned edges and mounted on one of said edges, stitches securing said edges and welt together, a flexible tubular casing of soft material mounted on the other of said edges, and a stiff flexible wire extending through said casing, said flexible tubular casing having wide edge flanges the ends of which are secured to its respectively inturned edge and being foldable to cause said flexible wire to be disposed at the junction of said sheet of material and its respective inturned edge to which said tubular casing is attached, and means for maintaining said tubular casing in this folded condition.

2. A reinforced seam for bags, comprising a flexible sheet of relatively soft material forming a

wall for the bag and having an inturned edge, another flexible sheet of relatively soft material at an angle to said sheet and forming another wall of said bag and having an inturned edge, a welt disposed between said inturned edges and mounted on one of said edges, stitches securing said edges and welt together, a flexible tubular casing of soft material mounted on the other of said edges, and a stiff flexible wire extending through said casing, said flexible tubular casing having wide edge flanges the ends of which are secured to its respectively inturned edge and being foldable to cause said flexible wire to be disposed at the junction of said sheet of material and its respective inturned edge to which said tubular casing is attached, and means for maintaining said tubular casing in this folded condition, said means comprising snap fastener elements located between the adjacent faces of said edge flanges and the respective inturned edge to which said casing is attached.

3. In a bag having flexible walls extended at right angles to each other with adjacent edges turned in and secured together with a welt disposed between the adjacent faces thereof, a tubular casing of flexible material, said tubular casing comprising a tube portion and a web portion, said web portion being formed of two strips of material respectively extending from said tube portion, said strips being secured together in face engagement with one another and being mounted on the inside face of one of said inturned edges, and a stiff wire extending through said tube portion for reinforcing said welt to stiffen and shape

35 said bag.

4. In a bag having flexible walls extended at right angles to each other with adjacent edges turned in and secured together with a welt disposed between the adjacent faces thereof, a tubular casing of flexible material, said tubular casing including a tube portion and a web portion, said web portion being mounted on the inside face of one of said inturned edges, and a stiff wire extending through said tube portion for reinforcing said welt to stiffen and shape said bag, said tube portion normally extending freely into said bag, and means for holding said tube portion in a folded position in which said stiff wire will be disposed in the junction of one of said inturned edges and its respective wall.

5. In a bag having flexible walls extended at right angles to each other with adjacent edges turned in and secured together with a welt disposed between the adjacent faces thereof, a tubular casing of flexible material, said tubular casing comprising a tube portion and a web portion, said web portion being mounted on the inside face of one of said inturned edges, and a stiff wire extending through said tube portion for reinforcing said welt to stiffen and shape said bag, said tube portion normally extending freely into said bag, and means for holding said tube portion in a folded position in which said stiff wire will be disposed in the junction of one of said inturned edges and its respective wall, comprising cooperative snap fastener elements mounted on said web portion and one of said inturned edges and engageable with each other for holding said tube portion folded over.
